UNDER-HUNG EAVES TROUGH HANGER

Charles C. Strayer, Johnstown, Pa.

Application January 4, 1937, Serial No. 119,012

2 Claims. (CL. 248—48.2)

This invention relates to eaves trough hangers of the under-hung type and has for its object to provide a comparatively simple and inexpensive device of this character which may be quickly and conveniently secured to a building beneath the eaves of the roof and by means of which a trough or gutter may be securely held in position without the employment of nails, wires and similar fastening devices.

10 A further object of the invention is to provide an eaves trough hanger comprising coacting hanger members, one of which is detachably secured to and adjustable vertically of a supporting bracket and the other provided with means 15 for gripping and supporting an eaves trough.

A further object is to provide the upper hanger member with means for automatically gripping the supporting bracket and the lower hanger member with means for detachable engagement 20 with the adjacent end of the upper member and said supporting bracket respectively.

25 A further object is to provide means for temporarily supporting a trough or gutter in proper position beneath the eaves of a roof preparatory to applying the permanent hangers thereto.

A still further object of the invention is generally to improve this class of devices so as to increase their utility, durability and efficiency.

In the accompanying drawings forming a part 30 of this specification and in which similar numerals of reference indicate corresponding parts in all the figures of the drawings:

Figure 1 is a perspective view of an under-hung eaves trough hanger embodying the present 35 invention showing it in position on a building;

Figure 2 is a perspective view of a complete hanger detached;

Figure 3 is an enlarged perspective view of the inner or gripping end of the upper hanger member;

Figure 4 is a transverse sectional view showing in dotted lines the position assumed by the upper and lower hanger members when released to permit positioning of the trough or gutter;

45 Figure 5 is a side elevation, partly in section, of the temporary hanger, and

Figure 6 is a transverse sectional view taken on the line 6—6 of Figure 5.

The improved eaves trough hanger forming 50 the subject-matter of the present invention is shown attached to a building in which 5 designates the roof and 6 the overhanging eaves thereof. Secured at spaced intervals to the face of the building immediately below the eaves 55 are supporting brackets or holders 7, each pro-

vided with a substantially T-shaped head 8 having openings 9 formed therein for the reception of nails, screws or similar fastening devices, by means of which the brackets may be secured to the building. Each bracket is provided with a 5 depending standard 10 having one face thereof grooved and formed with spaced transverse perforations 11 for the purpose hereinafter referred to.

The hanger proper consists of upper and lower 10 hanger members 12 and 13, between which is supported the eaves trough or gutter, indicated at 14. The upper hanger member 12 is preferably angular in cross section, thereby defining a horizontal flange 15 and a vertical reinforcing web 15 16, the free end of the flange 15 being curved downwardly to form a depending extension 17 having a slot 18 therein, as shown. The inner end of the vertical web 16 terminates in a hook 19, the bill of which is adapted to embrace the 20 adjacent edge of the standard 10. Formed in the web in advance of the hook 19 are spaced incisions 20, the metal between the incisions being pressed outwardly to form a lateral locking lug 21 adapted to enter a selected opening 11 in 25 the standard of the adjacent supporting bracket whereby to permit the upper hanger member to be adjusted vertically of the bracket and supported in adjusted position. The rear end of the flange 15 of the upper hanger member is also 30 preferably cut-away to form a shoulder or abutment 22 defining a lug or boss 23 adapted to contact with the standard of the bracket at the opposite edge thereof from the hook 19.

It will thus be seen that the construction of 35 the inner end of the upper hanger member 12 is such that by disposing said inner end at a slight angle to the standard 10 of the supporting bracket the locking lug 21 may be inserted in any one of the openings 11 when by allowing the upper 40 hanger member to assume a horizontal position the hook 19 and abutment or shoulder 22 will grip the opposite edges of the bracket so as to hold said upper hanger member in adjusted 45 position.

The lower hanger member 13 is curved to conform to the curvature of the bottom of the eaves trough 14, said lower hanger being provided at its inner end with a lateral pin 24 adapted to enter a selected opening 11 in the adjacent 50 bracket. The outer end of the lower hanger member 13 is provided with a depending hook 25 which fits within the slot 18 of the upper hanger member whereby said hanger members will coact to grip and support the eaves trough. 55

The upper edge of the lower hanger member 18 at the rear of the hook 25 is preferably provided with a concave seat 26 adapted to receive the bead or rolled edge 27 of the eaves trough. 5 From the foregoing, it will be understood that, when the hooked end 25 of the lower hanger member is inserted in the slot 18 and the pin 24 at the inner end of said lower member is inserted in a selected opening 14 in the supporting bracket, a clamping or gripping action will be exerted on the gutter and this clamping action is also exerted on the rolled edge of said gutter.

In order to temporarily support the eaves trough or gutter in proper position beneath the 15 eaves of a roof preparatory to applying the permanent hangers, there is provided one or more temporary supports 28 having concave seats 29 for the reception of the eaves trough and each having its inner end provided with a terminal hook 30 and a lateral locking pin 31 similar in construction to the hook 19 and locking pin 21 of the main hanger member.

In operation one or more of the temporary hangers 28 are positioned on the supporting 25 brackets and the eaves trough or gutter elevated and allowed to rest in the seats of the temporary hangers. The permanent hangers are then attached in the manner before described to the supporting brackets, after which the temporary hangers 28 are removed. If desired, the web 16 30 of the upper hanger member may be formed with an opening 32 adapted to receive one end of a wire 33, the opposite end of which is extended through one of the openings in the adjacent supporting bracket and coiled or twisted so as to provide an additional support for the hanger. It will, of course, be understood that the devices 35 may be made in different sizes and shapes to conform to the size and shape of the gutter to be supported and where the gutter is not formed

40 with a rolled edge or bead the seat 26 in the lower hanger member may be omitted without departing from the spirit of the invention.

Having thus described the invention, what is claimed as new is:

1. A device of the class described comprising a supporting bracket including a standard having spaced openings therein, and upper and lower hanger members coacting to grip an eaves trough between them, the upper hanger member having 10 its outer end provided with a seat and its inner end formed with a hook adapted to embrace the standard, and a locking lug adapted to enter one of the openings in said standard, the lower hanger member being provided with a terminal hook 15 adapted to enter the seat in the upper hanger member and having a lateral pin at its inner end adapted to enter a selected opening in the adjacent standard.

2. A device of the class described comprising a 20 supporting bracket having a depending standard formed with spaced openings, and coacting upper and lower hanger members adapted to grip an eaves trough between them, the outer end of the upper hanger member being curved downwardly 25 and provided with a seat and the inner end of said upper hanger member being provided with a hook adapted to embrace the standard and a lateral locking pin adapted to enter one of the 30 openings in said standard, there being a shoulder formed on the upper hanger member in advance of the locking pin and adapted to engage the standard, the lower hanger member being provided at one end thereof with a hook for engagement with the seat in the upper hanger 35 member and having its inner end provided with a lateral pin adapted to fit in a selected opening in the standard.

CHARLES C. STRAYER.
